UNITED STATES PATENT OFFICE.

JESSE G. VINCENT, OF DETROIT, MICHIGAN, ASSIGNOR TO HUDSON MOTOR CAR COMPANY, OF DETROIT, MICHIGAN, A CORPORATION OF MICHIGAN.

LUBRICATOR.

1,063,143.

Specification of Letters Patent.

Patented May 27, 1913.

Application filed July 2, 1912. Serial No. 707,191.

To all whom it may concern:

Be it known that I, JESSE G. VINCENT, a citizen of the United States of America, residing at Detroit, in the county of Wayne 5 and State of Michigan, have invented certain new and useful Improvements in Lubricators, of which the following is a specification, reference being had therein to the accompanying drawings.

10 The invention relates to lubricators and has particular reference to the automatic controlling means for the lubricant distribution and the association of the same with a pump as hereinafter set forth.

15 In the drawings: Figure 1 is a vertical central section. Fig. 2 is an elevation, partly in section.

20 A is a pump, which, as shown, is of the plunger type and is mounted upon the casing B of an engine. The plunger C, which engages the pump barrel, is provided with a head D engaging the cam E on the engine cam-shaft F, while a spring G yieldably holds the head D in contact with the cam.

25 The pump barrel is provided with inlet and outlet ports, preferably formed respectively by downwardly and upwardly extending portions H and I of the casing B. The outlet I is provided with a plurality of 30 branch connections and, as shown, there are two branches extending laterally upon opposite sides.

35 J and K are check valves, preferably balls, respectively controlling the inlet and outlet ports.

40 To control the distribution of the lubricant to the several branch conduits through which it is fed, I have devised an automatic valve which is opened by the pressure developed by the pump and proportions the distribution to the several conduits. This 45 valve preferably comprises a piston L operating in a cylinder M, a spring N operating to press said piston downward against a stop O. The branch conduits P and Q connect with the cylinder M, and, where the piston is in its depressed position, are completely cut off from communication with the outlet from the pump barrel. When, however, 50 the pump is in operation the pressure developed thereby will force the piston L upward against the tension of the spring N, thereby uncovering the ports of the conduits P and Q and permitting the lubri-

cant to pass therethrough. As shown, the 55 conduits P and Q are of equal capacity and are opened equally by the movement of the piston L; but where the conduits are of different capacity the volume of oil distributed to each may be proportioned by correspondingly proportioning the area of the ports opened by the valve. The valve L may be inserted through the upper end of the cylinder M, which is provided with a suitable cap R, also forming an abutment 60 for the spring N. The stop pin O, in addition to limiting the downward movement of the piston, forms an upward limit for the ball check valve K.

S is a nipple on the casing B for connecting a conduit T to the outlet passage of the pump below the valve L, which conduit T leads to a suitable pressure gage for indicating when the pump is in operation.

U is a by-pass between the upper end of 75 the cylinder M and one of the branch conduits, which provides for the displacement of the piston as it moves upward.

The construction as described forms an exceedingly simple means of distributing 80 proportionate amounts of lubricant through a plurality of conduits from a single pump. Furthermore, as the valve L is opened by the pressure developed by the pump the pressure gage will positively indicate 85 when the device is in operation.

What I claim as my invention is:

1. The combination with a pump provided with inlet and outlet connections of a plurality of branch connections to the outlet, 90 and a valve for simultaneously controlling said connections, variably positioned, by the pressure developed by said pump.

2. The combination with a pump having inlet and outlet connection and a plurality 95 of branch connections for said outlet, of a self-closing valve controlling communication between said outlet and the several branch connections, said valve being subjected to the pressure developed in the main outlet to 100 open the same.

3. The combination with a pump having inlet and outlet connections and a plurality of branch connections for said outlet, of a piston valve for simultaneously controlling 105 communication between said outlet and the several branch connections, one end of said piston being subjected to the pressure devel-

oped in the main outlet and being operated thereby to its open position, and a spring for closing said valve.

4. The combination with a pump having 5 inlet and outlet connections of a cylinder connected with said outlet, a plurality of branch connections respectively communicating with ports in said cylinder, a piston movable in said cylinder to simultaneously 10 and proportionately open and close said ports, one end of said piston being subjected to the pressure developed by said pump, and a spring for moving said piston to a position in which said ports are closed.

15 5. The combination with a casing forming a pump barrel of a plunger pump in said barrel, valve controlled inlet and outlet connections to said barrel, a cylinder with which said outlet communicates, a piston 20 valve in said cylinder, a plurality of branch conduits communicating with ports in said cylinder controlled by said valve, and a spring for closing said valve against the pressure developed by said pump.

25 6. The combination with a pump having valve controlled inlet and outlet connection, of a cylinder with which said outlet communicates beyond the valve therein, a piston valve in said cylinder, a plurality of branch

30 conduits connecting with ports in said cylinder, controlled by said piston valve, a spring for closing said valve against the pressure developed by said pump, and a connection on the said cylinder between said valves for leading to an indicator.

35 7. The combination of a casing having transversely extending pump and valve barrels, a plunger in said pump barrel, a piston valve in said valve barrel, a check valve between said pump barrel and valve barrel, a 40 plurality of branch conduits connecting with ports in said valve barrel controlled by the piston valve therein, a spring for moving said piston valve to the closed position, and a common stop for said piston and check 45 valves arranged therebetween.

8. The combination with a pump provided with inlet and outlet connections, of a plurality of branch connections for said outlet, and means governed by the pressure developed by the pump for correspondingly controlling the branch connections.

50 In testimony whereof I affix my signature in presence of two witnesses.

JESSE G. VINCENT.
